UNITED STATES PATENT OFFICE.

SAMUEL WARE, OF GENESEE, IDAHO.

GATE.

SPECIFICATION forming part of Letters Patent No. 742,763, dated October 27, 1903.

Application filed February 24, 1903. Serial No. 144,882. (No model.)

To all whom it may concern:

Be it known that I, SAMUEL WARE, a citizen of the United States, residing at Genesee, in the county of Latah and State of Idaho, have invented new and useful Improvements 5 in Gates, of which the following is a specification.

My invention relates to those swinging gates which are provided with hand-openers; and 10 it consists in a certain peculiar construction the novelty, utility, and practical advantages of which will be fully understood from the following description and claims when taken in connection with the accompanying drawings, in which—

Figure 1 is a broken perspective view of so much of a swinging gate as is necessary to illustrate my invention, the gate being shown as secured in its closed position. Fig. 2 is a 20 broken view, partly in elevation and partly in vertical section, of the gate in its closed position. Fig. 3 is a detail section taken on the broken line 3 3 of Fig. 2, and Fig. 4 is a detail section taken in the plane indicated by the 25 broken line 4 4 of Fig. 2.

Similar letters of reference designate corresponding parts in all of the several views of the drawings, referring to which—

A is a post fixed in the ground and equipped 30 with a keeper *a*, Fig. 4, having a central notch *b* and beveled edges *c*, leading to said notch; B, a fixed post of circular form in cross-section, arranged opposite the post A and slightly canted or inclined toward the 35 same; C, the swinging gate; D, a post fixed in the ground at a suitable distance from the post B and provided with sheaves *d* *e*, Fig. 1, and E a post fixed in the ground at a point between the post B and the post D and 40 equipped with a pivoted keeper *f* and an open frame *g* for limiting the vertical movement of said keeper and normally retaining it in the position shown in Fig. 1. Posts similar in all respects to the posts D E, but not shown, 45 are provided at the opposite side of the post B with reference to said posts, D E. The posts D are preferably connected with the posts E by bars F, only one of which is shown, while the posts E are connected together by 50 a bar G, in which the upper end of the fixed post B is arranged, and also by a lower bar G'. The post B is provided in its lower portion

with three (more or less) diametrical apertures *h*, disposed toward the post A, and in its upper portion with three (more or less) similar apertures *i*. In one of the apertures *h* is 55 removably secured a journal *j*, Fig. 2, which carries antifriction-rollers *k*, while in one of the apertures *i* is removably secured a journal *l*, which carries a single antifriction- 60 roller *m*.

The gate C may, in general, be of any suitable construction without involving a departure from the scope of my invention and may when desired be equipped with a barbed-wire 65 guard H, designed to prevent the passage of hogs beneath it. Said gate is provided at the inner end of its lower bar with a sleeve I and at the inner end of its upper bar with a loop or eye J, both of which are loosely mounted 70 on the post B. The sleeve I has notches *n* in its lower end designed to receive the antifriction-rollers *k*, and the loop or eye J carries an antifriction-roller *p*, arranged to travel against the post B during the vertical movements of the gate. The gate is further provided with upper and lower hooks *r*, Fig. 2, and two (more or less) apertures *s*, in one of which is removably secured a latch-bolt *t*, 75 equipped with an antifriction-roller *u*. 8c

K, Fig. 1, is a cable passed over a sheave L, hung from the bar G, and connected at one end to the gate and having a counterbalance-weight M at its opposite end.

N N are sheaves mounted on a frame P, 85 connected to the bar G'; Q Q, guides connected to said bar and arranged adjacent to the sheaves N, and R R cables connected at one end to hooks *r* of the gate and passed around the sheaves N, through the guides Q, 90 and around the sheaves *d e* on posts D, and having handles S at their opposite ends.

It will be readily appreciated from the foregoing that when the gate C is secured in its closed position and a person draws the handle of one of the cables R downwardly the gate will first be raised, with the assistance of the weight M, so as to disengage the latch *t* from the keeper *a*, and will then be swung on the post B in a direction away from such person and into engagement with one of the keepers *f*, which will serve to retain it in an open position; also, that when the handle of the other cable R is drawn downwardly the 100

gate will be lifted out of engagement with the mentioned keeper *f* and will then swing by reason of gravity into its closed position, this latter because of the cant or inclination 5 of the post *B* toward the post *A*. From the foregoing it follows that a person on horseback or in a vehicle is enabled to conveniently open and close the gate with but a minimum amount of effort. When the gate is opened 10 in the manner described, but not sufficiently far to carry it into engagement with one of the keepers *f*, it will be seen that the gate will swing closed as soon as the cable *R*, used to open it, is released. This is advantageous, 15 since a person may open and drive stock through the gate and then effect the closing of the gate without passing through the same.

The plurality of apertures *h* and *i* in post *B*, the plurality of apertures *s* in the gate, 20 and the plurality of hooks *r* on the gate are advantageous, since they permit the gate to be raised when there is sufficient snow on the ground to interfere with its movements. When it is desired to raise the gate as stated, 25 the journal *j* is placed in the middle one of the apertures *h* of post *B*, the journal *l* is placed in the middle one of the apertures *i* of said post, the latch *t* is placed in the lower aperture *s* of the gate, and the cables *R* are 30 connected to the lower hooks *r* of the gate.

I have shown the post *B* as provided with three apertures *h* and three apertures *i*. When the journal *l* is placed in the upper aperture *i* and the journal *j* in the upper aperture *h*, it will be necessary to place the latch *t* in an additional lower aperture in the gate and provide an additional lower hook *r* on the gate. I have not deemed it necessary, 35 however, to illustrate said additional aperture and hook.

During the swinging movements of the gate the sleeve *I* will bear on the rollers *k* and the loop or eye *J* will bear against the roller *m*, with the result that there will be but a minimum 40 amount of friction between the gate and post *B*. When the gate assumes a closed position, the notches *n* in sleeve *I* will receive the antifriction-rollers *k* on journal *j*, and thereby assist the bolt *t* and keeper *a* in retaining the gate in its closed position.

I have entered into a detailed description of the construction and relative arrangement of the parts embraced in the present and preferred embodiment of my invention in order 45 to impart a full, clear, and exact understanding of the same. I do not desire, however, to be understood as confining myself to such specific construction and arrangement of parts, as such changes or modifications may 50 be made in practice as fairly fall within the scope of my invention as claimed.

Having described my invention, what I claim, and desire to secure by Letters Patent, is—

65 1. The combination of a post provided with a keeper, a post canted or inclined toward the keeper-post, a vertically-movable, swinging

gate mounted on the canted or inclined post, and having a latch adapted to engage the keeper, a counterbalance-weight connected 70 with the gate, and means connected with the gate for enabling a person at a distance from the gate to open the same.

2. The combination of a canted or inclined post, a journal arranged therein, antifriction-rollers mounted on the journal, and disposed 75 at opposite sides of the post, a vertically-movable, swinging gate, a sleeve fixed with respect to the gate, and loosely mounted on the post, and having notches in its lower end 80 adapted to receive the antifriction-rollers, a sheave mounted above the gate, a cable passed over said sheave and connected at one end to the gate, a weight connected to the opposite end of said cable, and means for raising and 85 swinging the gate.

3. The combination of a canted or inclined post, a journal arranged therein, antifriction-rollers mounted on the journal, and disposed 90 at opposite sides of the post, a journal arranged in the post above the first-mentioned journal, an antifriction-roller mounted on the upper journal, a vertically-movable, swinging gate having a loop or eye mounted on the post below the upper journal, and adapted to 95 bear against the antifriction-roller thereon, a sleeve fixed with respect to the gate, and loosely mounted on the post, above the lower journal, and having notches in its lower end adapted to receive the antifriction-rollers, a 100 sheave mounted above the gate, a cable passed over said sheave, and connected at one end to the gate, a weight connected to the opposite end of said cable, and means for raising and swinging the gate.

4. The combination of a post provided with a keeper, a post canted or inclined toward the keeper-post, a vertically-movable, swinging gate mounted on the canted post and having a latch adapted to engage the keeper, a keeper 110 for engaging the gate, and holding it in its open position, and means for raising and swinging the gate.

5. The combination of a post provided with a keeper, a post inclined toward the keeper-post, a frame arranged adjacent to the latter post, a vertically-movable, swinging gate mounted on the inclined post, and having a latch adapted to engage the keeper, a sheave mounted on the frame above the gate, a cable 115 connected to the gate and passed over the sheave, a weight connected to said cable, sheaves and guides mounted on the frame above the gate and at either side of the inclined post, keepers connected to the frame 120 at either side of the gate, and adapted to engage the gate when the same is open, and cables connected to the gate, and passed around the sheaves and through the guides.

6. The combination of an inclined post, 130 lower and upper journals arranged therein, antifriction-rollers mounted on the lower journal, and arranged at opposite sides of the post, an antifriction-roller mounted on the

upper journal, a vertically-movable, swinging gate having an eye mounted on the post below the upper antifriction-roller, a sleeve fixed to the gate, and mounted on the post, 5 and having notches in its lower end adapted to receive the lower antifriction-rollers, a frame arranged adjacent to the inclined post, a sheave connected to said frame above the gate, a cable passed over said sheave, and 10 connected at one end to the gate, and having a weight at its opposite end, keepers connected to the frame at opposite sides of the gate, sheaves and guides connected to the frame above the gate and at opposite sides 15 of the post, and cables connected to the gate and passed around the latter sheaves and through the guides.

7. The combination of an inclined post having a plurality of lower apertures and a plurality of upper apertures, lower and upper 20

journals removably arranged in apertures of the post, antifriction-rollers mounted on the lower journal, and arranged at opposite sides of the post, an antifriction-roller arranged on the upper journal, a vertically-movable, 25 swinging gate having an eye mounted on the post; said eye having notches in its lower end adapted to receive the lower antifriction-rollers, a counterbalance-weight connected with the gate, and cables for raising and 30 swinging the gate detachably connected to the same.

In testimony whereof I have hereunto set my hand in presence of two subscribing witnesses.

SAMUEL WARE.
